UNITED STATES PATENT OFFICE.

JOSEPH GOULDBOURN AND FRED RICKS, OF LEICESTER, ENGLAND, ASSIGNEES TO
UNITED SHOE MACHINERY CORPORATION, OF PATERSON, NEW JERSEY, A COR-
PORATION OF NEW JERSEY.

GRINDING MACHINE.

Application filed August 8, 1921. Serial No. 490,524.

To all whom it may concern:

Be it known that we, JOSEPH GOULDBOURN and FRED RICKS, subjects of the King of England, and residing at Leicester, Leicestershire, England, have invented certain Improvements in Grinding Machines, of which the following description, in connection with the accompanying drawings, is a specification, like reference characters on 10 the drawings indicating like parts in the several figures.

This invention relates to grinding apparatus for stock cutting tools and is herein shown as embodied in a machine for grinding 15 the cutting blades of a nailing machine.

In machines of the type known as taper-nail tacking machines, an example of which is shown in United States Letters Patent No. 490,625, granted Jan. 24, 1893, on an application of L. Goddu, there are two shearing blades which cut fasteners from a strip of metal stock. The blades are formed of plates, the cutting edges of which are substantially radial to and extend between concentrically curved opposite edges of the plates. One blade in the machine is stationary and considerably thicker than the other blade which is movable. The cutting edges of the two plates of a pair differ some- 25 what in inclination so that upon movement of the movable blade about the center of its curved edges, the strip from which the fastener is to be formed has a portion severed from it by a scissor-like action. This 30 dissimilarity of the blades has heretofore led to some difficulties and uncertainty in their grinding.

An object of the invention is to provide a machine for accurate and easy grinding of 40 dissimilar blades such as these without likelihood of error. As a feature of the invention, there is provided, in the illustrated construction, a support for either of the two blades of a pair, common means to locate similar parts of either blade at a definite point on the support, and a further locating means constraining other parts of the blades to take up necessarily different positions with relation to this support so 45 that each blade will be presented to the grinder in the appropriate position for accurately and differentially grinding that blade.

Another feature of the invention relates

to an improved construction by which the extent and accuracy of the grinding is indicated. As shown, there is provided a movable blade support, means associated with the support for locating the blade in the proper position for securing the desired angle of ground edge with relation to the body of the blade, a grinder, a gage to indicate when the edge of the blade has been correctly ground, and means controlled by the movement of the support between operative 60 and inoperative grinding positions, for moving the gage into and out of indicating position.

Other objects and advantages of the invention will appear from a consideration of 70 the following specification and accompanying drawings, in which—

Fig. 1 is a front view of the grinding device;

Fig. 2 is a plan view showing the tool 75 support out of grinding position and the gauge operative to indicate the completion of grinding;

Fig. 3 is a plan view showing the support moved up toward the wheel; and 80

Fig. 4 is a side elevation of a modified form of the mechanism for operating the gage.

In this construction a grinding wheel 2, shaped as a disk with a cylindrical peripheral rim, is fixed on one end of a horizontal shaft which is rotatably mounted in suitable bearings formed on a frame 4. Fixed in the frame 4 of the machine parallel to but below and in front of the grinding 85 wheel shaft is a fixed horizontal shaft 6 which has mounted on it a vertically disposed arm 8. The arm is arranged to be rocked by hand on the fixed shaft between limit stops formed by depending lugs 10 90 on the hub of the arm 8 and a horizontal pin 12 positioned between the lugs and extending from the frame. The arm 8 can also be moved with its hub 14 along the fixed shaft 6 by any suitable mechanism 100 exemplified by the hand wheel 16. Rotation of the hand wheel 16 moves the hub 14 axially of the shaft 6 carrying the arm 8 with it. The manual rocking or swinging movement causes the blade or cutter (which as will hereinafter be described, is supported on the upper end of the arm 8) to be moved across the face of the grinding wheel,

and movement of the arm 8 along the shaft 6 adjusts the blade towards this face of the grinding wheel in a direction parallel to the rim.

- 5 The arm 8 at its upper end is formed as a table or support 20 the upper face of which is inclined downwardly towards the face of the grinding wheel so that the edge of the blade is backed off at the desired angle. The 10 upper face of the table 20 has fixed in it two pins or abutments 22, 24 perpendicular to the face, against which the concave side of the blade is positioned. The pin 22 which engages the blade nearest the cutting edge is 15 a plain cylindrical pin and the other, 24, is a fixed abutment of irregular shape having a cylindrical head of larger diameter than but coaxial with its cylindrical shank 26 and the head is raised a sufficient distance above 20 the table to allow of the thinner of the two blades, usual in the type of machine described in the specification above referred to, i. e. the moving one, only just passing under the head 24 and being positioned against 25 the shank 26, as shown in the drawings. The thicker of the two blades is positioned against the head and is usually bevelled off as shown by the face 28 in Fig. 1 so as to reduce to a minimum the amount of grinding 30 required upon the end face 30 of which the lower edge is the cutting edge. The necessity for the different positioning of the two blades, in relation to the pin 22 against which both in turn rest, arises from the fact 35 that the cutting edge of the thick or stationary blade is radial to the center of curvature of the concave side of the blade while the cutting edge of the thin blade is on a line which, if projected, would pass to one 40 side of that center. It will be observed, then, that the two types of blades have similarly shaped bodies, differently disposed cutting edges, and another varying characteristic, here, their thickness.
- 45 The blade is clamped in position against the pins 22, 24 by a block 32 engaging the convex side of the blade, which block is slidingly mounted in a groove more or less radial to the cutters and formed in the upper 50 face of the table. The block has a recess in which is positioned an eccentric 34 formed on a hand lever 36. The hand lever is rotatably mounted on a pin 38 passing through the table 20 and a slot in the block. A pin 55 39 projecting upwardly from the table limits the movement of the hand lever in its cutter releasing movement.

A gauge face 40 by which the operator 60 may determine when either of the blades has been correctly ground, is formed on an arm 42 fixed on the upper end of a shaft 44 which is perpendicular to the top face of the table and is rotatably mounted in a bearing 46 formed on the table arm 8. On 65 the lower end of the shaft 44 is fixed a sec-

ond arm 48 which has rotatably mounted on its end a depending pin 50 the upper end of which has fixed on it a collar and the lower end of which is connected by a transverse pivot 52 to one end of a rod 54. The other 70 end of the rod 54 passes through an extension 56 of the frame of the machine and has on its end a compression spring 58 which is confined between the back of the extension 56 and a collar 60 fixed on the end of the 75 rod. On the side of the extension remote from the spring the rod 54 has formed on it a collar 62 which enters a recess formed in the extension.

Starting from the position shown in Fig. 80 2, as the blade carrying arm 8 is swung about the fixed shaft 6 towards the grinding wheel the collar 62 on the rod 54 is moved into engagement with the bottom of the recess and during continued movement of the 85 blade carrying arm, the arm 48 is therefore turned on its axis and the gauge arm 42 is swung outwardly away from the blade into a position (shown in Fig. 3) in which it does not obstruct the movement of the 90 blade on to and across the grinding wheel. When the blade carrying arm is swung in the reverse direction the gauge arm will swing towards the blade and during the last portion of such movement, when the blade 95 is quite clear of the grinding wheel, the spring 58 will be slightly compressed thereby ensuring full movement of the gauge arm towards the blade. The gauge arm 42 is limited in its movement towards the blade 100 by the engagement of a hemispherically ended pin 64 on the gauge arm with a flat faced stop 66 on the table 20.

Instead of the mechanism above described for moving the gauge, there may be provided 105 to operate the arm 42 a fixed cam piece 70 (Fig. 4) fast on the front part of the frame 4 and acting directly on a ball 72 depending from the arm 48 to cam the arm 48 away from the blade in the first portion 110 of the movement of the table arm 8 towards the grinding wheel, there being a spring 74 coiled about the shaft 44 (bearing at one end on the arm 42 and at the other end on the arm 8) to move the arm 42 towards the 115 blade, near the end of the return movement of the arm 8 away from the grinding wheel when the ball 72 reaches the drop in the cam.

Referring to Fig. 3, the parts are shown in 120 a position in which, in order to allow a worn blade to be ground, the arm 8 has been backed away from the grinding wheel along the shaft 6 and the blade (shown dotted) has its edge worn so as to project farther 125 over the edge of the table 20 at the convex side of the cutter than at the concave side. The cutting edge requires to be ground until it is parallel with the table edge along the whole length of cutting edge. The op- 130

erator will therefore swing the arm 8 backwards and forwards on the shaft 6, that is, towards and away from an observer of Fig. 1, so that the blade moves across the grinding wheel rim; meantime he will gradually move the arm along the shaft 6 by means of the hand wheel 16, and also will occasionally move the arm through a larger arc clear of the grinding wheel to the position shown 5 in Fig. 2 so as to bring the gauge face 40 up to the cutting edge so that he may observe what further grinding is required. The simultaneous engagement of the pin 64 and the stop 66 and the engagement of the 10 cutting edge along its whole length with the gauge face 40 indicates that the blade (either the fixed or stationary one) has been correctly ground.

Having thus described our invention, what 20 we claim as new and desire to secure by Letters Patent of the United States is:

1. In a machine of the class described, a grinder, a support for the similar shaped bodies of the tools of a set which vary as to 25 cutting edge and one other characteristic, common means to locate similar parts of the bodies of the tools of a set at a definite point, and locating means engaging other parts of the similar shaped bodies of said tools, said 30 locating means being arranged to co-operate with the varying characteristic of the tools to cause them to take different positions with relation to the support whereby their edges will be ground at different angles.
2. In a machine of the class described, a 35 grinder, a support for differing tools of a set, common means to locate similar parts of the tools of a set at a definite point, and a further locating means engaging other parts of said tools and comprising a member having portions which vary in position 40 with their distances from the support whereby tools of different thicknesses are differently located for grinding.
3. In a machine of the class described, a 45 grinder, a support for differing tools of a set, and means for locating the various tools in different positions for grinding comprising an abutment of irregular shape arranged to provide tool supporting surfaces 50 at different distances from the tool support and to cause the various tools to assume different positions on said support.
4. In a machine of the class described, a 55 grinder, a support for either of a pair of blades of different thicknesses, a stud projecting from the support for locating similar parts of either of said blades at a definite point, and a further locating means 60 comprising a pin for engagement with the thinner one of said blades to locate it in a position for grinding, and a head on said pin for engagement with the thicker of said blades to locate it in a different position for 65 grinding.

5. In a machine of the class described, a grinder, a movable tool support, means for securing a tool on the support, a gauge to indicate when the edge of the tool has been correctly ground, and means, controlled by the movement of the tool support between operative and inoperative grinding positions, for moving the gauge into and out of indicating position.

6. In a machine of the class described, a 75 grinder, a movable blade support, means for securing a blade on the support, a gauge movably mounted on the support and arranged to engage the edge of the blade, a fixed member, and means connected to the 80 movable gauge and engageable with the fixed member for moving the gauge against the edge of the blade during movement of the blade support to indicate the degree of grinding.

7. In a machine of the class described, a grinder, a movable blade support, means for securing the blade on the support, a gauge pivoted on the support, and arranged to swing against the edge of the blade, an arm secured to the gauge pivot, a fixed member, and a rod secured to the arm and connected to the fixed member for swinging the gauge during movement of the blade support.

8. In a machine of the class described, a 95 grinder, a blade support, said grinder and blade support being relatively movable means for securing the blade on the support, a gauge pivoted on the support and arranged to engage the edge of the blade, and means set in operation by said relative movement for swinging the gauge to a position where it will indicate the degree of grinding.

9. In a machine of the class described, a 105 grinder, a blade support, means for securing the blade on the support, a gauge pivoted on the support, means for swinging the gauge against the edge of the blade and means carried by the gauge for engagement 110 with the blade support to indicate the completion of the grinding.

10. In a machine of the class described, a grinder, a movable blade support, means for securing the blade to the support, a gauge pivoted on the support and arranged to engage the edge of the blade, means operated by the movement of the blade support for swinging the gauge out of operative position and a spring tending to swing 120 the gauge against the blade.

11. In a machine of the class described, a grinder, a support for a blade, means for locating the blade on the support for grinding, and means for both moving the blade 125 against the locating means and clamping it in position.

12. In a machine for grinding the different blades of a set, a grinder, a blade support, means for locating the blades differ- 130

ently upon the support for securing the desired angle of ground edge in relation to the body of the blade, and a clamp to hold either of the blades against said locating means in correct position on the support for grinding.

13. In a machine for grinding the different blades of a set, a grinder, a support for the blades of differing form, and a fixed 10 abutment constructed and arranged to cause the edges of the differing blades to select a common grinding station on the support while the shape of the abutment forces the bodies of the blades to occupy different positions in accordance with their differences in form.

14. In a machine of the class described, a grinder, a movable blade support, means for securing the blade to the support, a gauge movably mounted on the support to engage the blade, a spring connected to the gauge and to the support for holding the gauge against the blade, and means movable with the support and operating by contact with a fixed member for moving the gauge away from the blade against the tension of said spring.

In testimony whereof we have signed our names to this specification.

JOSEPH GOULDBOURN.
FRED RICKS.
